Fig. 5

Fig. 7

Fig. 8

Fig. 9

Fig. 10

FIG. 1 is a perspective view of a hair dryer showing our new design;

FIG. 2 is a front view thereof;

FIG. 3 is an elevational view of the side opposite that shown in FIG. 1;

FIG. 4 is a top view thereof;

FIG. 5 is a rear view thereof;

FIG. 6 is a perspective view thereof similar to that of FIG. 1 but with the cover in open position;

FIG. 7 is a front view thereof with the cover removed;

FIG. 8 is a side elevational view thereof similar to that of FIG. 3 but with the cover removed;

FIG. 9 is a top view thereof with the cover removed; and

FIG. 10 is a rear view thereof with the cover removed.

The dominant features of our design are shown in solid lines.

We claim:

The ornamental design for a hair dryer, as shown and described.
